UNITED STATES PATENT OFFICE

JOHN WILLIAM PATRICK, OF ESSENDON, MELBOURNE, AUSTRALIA

ELECTRIC FUSE HOLDER FOR AUTOMOBILES

Application filed December 22, 1927, Serial No. 241,894, and in Australia July 8, 1927.

This invention relates to electric fuse holders for automobiles and its primary object is to provide a simple, inexpensive and efficient fuse holder which is adapted for attachment to the dash board or like part of an automobile and to removably accommodate a series of the ordinary automobile fuses in a rotary magazine, whereby in the event of a fuse burning out, a new fuse may be immediately brought into action by partial rotation of the magazine and without removing and renewing the burnt-out fuse until all of the fuses have been spent when they may be readily replaced by merely inserting new fuses into circumferentially spaced passages of the magazine.

Whilst electric fuses of the rotary magazine type are already known, such existing devices have the disadvantage that the individual fuses are fixedly mounted within the magazine, so that when all of the fuses have been spent it is necessary to provide an entirely new magazine, instead of merely inserting new standard fuses therein as is the case with the present invention. Moreover magazine fuses have not hitherto been adapted for mounting on the dashboard or like part of an automobile, for which purpose the present invention has been specially designed.

In order that this invention may be better understood, reference will now be made to the accompanying drawing which is to be taken as part of this specification and read herewith:—

Figure 1 is an external side view of a fuse holder according to the present invention.

Figure 2 is a sectional elevation of the fuse holder.

Figure 3 is a cross section on the line III—III in Figure 2.

Figure 4 is a detail view of a series of springs carried by a ring member as seen in Figure 2.

Figure 5 is a fragmentary detail view in section, showing a modified form of spring means for the fuses in the holder.

Figure 6 is a view showing a fuse holder according to the invention fitted to the instrument or dash board of an automobile.

The invention includes a base plate or

disc member 7 which may be suitably constructed from sheet metal and is provided with a central socket or cup shaped depression 8 to accommodate an insulating ring 9 through which and the bottom of said disc member coinciding central openings 11 are formed to pass a stationary axial spindle 12 which is insulated from said disc member. At the inner end of this spindle is a terminal screw 13 carrying suitable terminal nuts 14 to receive one of the electric conductors (not shown) leading to the fuse.

A contact pin 16 having at its inner end a similar terminal screw 17 and nuts 18 also passes through the bottom of the cup 8 and through the said insulating ring 9; the front face of the enlarged head 19 of this pin preferably being recessed as at 21 to receive the inner ends of the fuses 22 as they are successively brought into engagement with the contact pin 16 by rotation of the magazine 23.

The magazine is mounted rotatably upon the said axial spindle 12 and may be constructed of fibre or other suitable insulating material, and it is preferably of cylindrical shape. The magazine is provided with a central passage 24 to accommodate the axial spindle and is also provided with a series of circumferentially spaced passages 26 extending from end to end thereof for the purpose of accommodating the fuses 22 which may be of the tubular type commonly used on automobiles.

According to the embodiment shown in Figure 2, the said circumferentially spaced passages 26 also accommodate relatively light coiled springs 27 one of which presses against the outer end of each fuse 22 so that the inner end of the latter is forced yielding against the front face of the aforesaid insulating ring 9 and into the recess 21 of the contact pin 16 as the fuse is brought into alignment with the latter. The outer end portions of the springs 27 may be welded, soldered or otherwise suitably secured to a metal ring 28. An insulating strip 20 may be secured to the under face of the bottom wall of the cup or socket 8, having perforations for the passage of the terminals 13 and

17 therethrough; these perforations or openings being provided with struck-up marginal lips or flanges 25 that project into the openings in the aforesaid cup wall to prevent short-circuiting.

5 Covering the outer end of the rotatable magazine 23, the springs 27 and the metal ring 28 is a cap 29 which is preferably provided with a milled or like edge 30 and is 10 adapted to be turned with the magazine about the aforesaid axial spindle.

Passing through a central hole in the cap 29 into a coinciding screw threaded hole 31 in the outer end of the axial spindle 12 is a 15 set screw 32 having a milled or like head 33 whereby the cap is retained in place and the magazine may be normally held against rotation.

Screw holes 34 or the like are formed 20 through the base plate or disc 7 whereby the latter may be conveniently attached to the dashboard or instrument board 36 of an automobile as indicated in Figure 6.

In use, the current passes from one terminal through the axial spindle 12, the metal cap 29 and the metal ring 28 to the respective spring 27 and the fuse 22, which is engaging the contact pin 16 in the insulating ring 9, and thence through this contact pin to the 30 other terminal which is attached thereto. When a fuse 22 becomes burnt out or damaged, it is merely necessary to give the cap 29 on the magazine a partial turn so that the inner end of the next succeeding fuse 22 35 is brought into engagement with the contact pin 16, whereupon the new fuse is in position for use.

When all of the fuses have been spent, it is merely necessary to remove the set screw 40 32 and cap 29, whereupon the magazine 23 may be withdrawn from the axial spindle 12 and the used fuses slipped out and replaced by new ones, against the outer ends of which the springs 27 are positioned in the respective 45 passages 26 of the magazine. The cap 29 and set screw 33 are then again placed in position and the device is ready for further use.

Suitable indication marks may, if desired, 50 be placed upon the disc member 7 and the magazine 23 (for instance as at 44, 45 and 46 in Figures 1 and 3) to indicate the correct degree and direction of rotation of the magazine to bring the fuses successively into operative position.

According to the modification illustrated in Figure 5, the relatively light independent springs 27 are replaced by a single relatively 60 strong spring 37 which encircles the spindle 12 between the cap 29 and a metal ring 28. This ring is provided with a number of circumferentially spaced studs 38 which project into the respective fuse passages 26 in the 65 magazine 23, and thus resiliently hold the

fuses 22 against the outer face of the insulating ring 9.

Having now described my invention what I claim as new and desire to secure by Letters Patent is:—

70 1. An improved electric fuse holder for automobiles, comprising in combination, a cylindrical socket member adapted to be attached to the dash or instrument board of the vehicle, a ring of insulating material disposed within and adjacent an inner end wall of said socket member, a contact member extending through said insulating ring and said wall at a point which is off-set from the centre thereof, said contact member forming one of the electric terminals of the device, a spindle extending axially through the socket member and said insulating ring and forming the other electric terminal, a magazine rotatable about said spindle and having its inner surface contiguous with the outer surface of said ring, said magazine being provided with a number of circumferentially spaced and open ended longitudinal passageways each of which is adapted to removably and slidably 90 accommodate an electric fuse, means for electrically connecting said spindle with said fuses, spring means for pressing said fuses inwardly within their respective passageways, and a detachable cap at the outer end of the magazine for retaining said spring means in operative position.

95 2. In an electric fuse holder, the combination of a support, a magazine rotatably accommodated by said support, said magazine being provided with a number of circumferentially spaced and open ended longitudinal passageways each of which is adapted to removably and slidably accommodate an electric fuse, a contact member carried by said support in circumferential alignment with the fuse accommodating passageways of the magazine, and resilient means to press said fuses inwardly within their respective passageways so that by appropriate turning of the magazine any one of said fuses may be electrically connected with said contact member, said resilient means comprising a plate and a number of circumferentially spaced springs having their outer ends secured to said plate and their inner ends adapted to engage the outer ends of fuses in said magazine.

100 3. In an electric fuse holder, the combination of a support; a magazine rotatably mounted thereon and provided with a plurality of circumferentially-spaced, open-ended longitudinal passageways, each of which is adapted to removably and slidably accommodate an electric fuse; a plate at one 105 end of the magazine; a plurality of circumferentially-spaced springs carried by said plate and having their inner ends adapted to engage the outer ends of the fuses in said passageways and press the same inwardly 110

thereinto; and a cap removably fitted on said magazine end to hold the plate and springs normally in operative position.

4. An electric fuse holder, comprising a cup-shaped socket; a spindle extending axially therethrough; a magazine disposed within said socket for rotary movement about said spindle, said magazine being provided with a plurality of circumferentially-spaced, 10 open-ended longitudinal passageways, each of which is adapted to removably and slidably accommodate an electric fuse; a plate at one end of the magazine; a plurality of circumferentially-spaced springs carried by 15 said plate and having their inner ends adapted to engage the outer ends of the fuses in said passageways and press the same inwardly thereinto; and a cap removably fitted on said magazine end to hold the plate and 20 springs normally in operative position.

In testimony whereof I affix my signature.
J. W. PATRICK.
